UNITED STATES PATENT OFFICE.

HARRY G. NORWOOD, OF BALTIMORE, MARYLAND, ASSIGNOR TO WILLIAM FULD, OF BALTIMORE, MARYLAND.

WHEELED TOY.

1,376,570.

Specification of Letters Patent. Patented May 3, 1921.

Application filed August 12, 1920. Serial No. 402,982.

To all whom it may concern:

Be it known that I, HARRY G. Norwood, a citizen of the United States, residing at Baltimore and State of Maryland, have invented certain new and useful Improvements in Wheeled Toys, of which the following is a specification.

This invention relates to improvements in wheeled toys, and more particularly to 10 that type of toy which is provided with a plurality of wheels having their peripheries formed with flat surfaces, instead of round.

One object of the invention is to provide 15 a wheeled toy with a rocking device, said device being operated by means of the vibration or the up and down movement, due to the flat surfaces on the wheels of said toy.

Other objects will appear as the description proceeds.

20 In the accompanying drawings which form a part of this specification,

Figure 1 is a side elevation of my improved toy;

Fig. 2 is a detailed side elevation of the 25 wheel structure;

Fig. 3 is a plan view of the toy, showing the rocking figures, and

Fig. 4 is a side elevation of a toy of similar nature, but provided with only one pair 30 of wheels.

Like characters of reference are used throughout the following specification to designate corresponding parts.

The body or platform 1, of the toy is provided with one or a pair of brackets 2, extending downwardly therefrom, and carrying one or more axles 3, upon which the wheels 4, are mounted. These wheels 4 are formed with irregular peripheries.

40 Mounted upon the top of the platform 1, is a standard 7, which is provided with the bearing rod 8 in its upper end. Upon this rod 8 is pivotally mounted the parallel arms 9, the same being connected together at their outer ends by means of the pivot rods 10.

Figure toys 11, having bearings 12 are positioned on the rods 10, and are adapted to freely swing thereon.

A handle 13 or cord 14 may be attached to the platform 1, by which means the toy may 50 be pulled along the floor.

It will be apparent that when the toy is pulled along the floor, that the figure toys 11 will rock back and forth on the axle or rod 8, due to the vibratory or up and down 55 movement of the toy, caused by the peculiarly surfaced wheels as they bump along.

It will be understood that many minor changes in detail of construction may be resorted to without departure from the spirit 60 of the invention.

Having thus described my invention, what I claim as new and desire to secure by Letters Patent of the United States is:

1. A wheeled toy comprising wheels having irregular peripheries, a platform carried by said wheels, a standard on said platform, and a freely swinging rocker arm carried by said standard.

2. A wheeled toy comprising wheels having irregular peripheries, a platform carried by said wheels, a standard on said platform a freely swinging balanced rocker arm carried by said standard, and figure toys pivotally mounted on said rocker arm.

3. A wheeled toy comprising a body portion, brackets thereon, axles mounted between said brackets, wheels mounted on said axles, said wheels having irregular peripheries, a standard fixed to the body portion, a 70 shaft or bearing rod carried at the free end thereof, arms mounted on said bearing rod parallel with each other, figure toys pivotally mounted between said arms, and means for pulling the wheeled toy along the floor. 75

whereby the figure toys will rock, due to the up and down movement of the platform caused by the irregular peripheries of the wheels.

In testimony whereof I affix my signature 80 in the presence of two witnesses.

HARRY G. NORWOOD.

Witnesses:

WILLIAM FULD,

WILLIAM A. FULD.
